UNITED STATES PATENT OFFICE.

JOHN BRADY, OF NEW YORK, N. Y.

CAN-OPENER AND ICE-PICK.

SPECIFICATION forming part of Letters Patent No. 609,406, dated August 23, 1898.

Application filed September 11, 1897. Serial No. 651,390. (No model.)

To all whom it may concern:

Be it known that I, JOHN BRADY, a citizen of the United States, and a resident of New York, (Blackwell's Island,) county of New York, and State of New York, have invented 5 certain new and useful Improvements in a Can-Opener and Ice-Pick, of which the following is a specification, reference being had to the accompanying drawings, forming a part 10 thereof, in which similar letters of reference indicate corresponding parts.

My invention relates to an improved combined can-opener and ice-pick, the object thereof being to provide an article which is 15 cheap, durable, and simple in construction and adapted for use on all sizes of cans.

The invention will be hereinafter fully described, and specifically set forth in the annexed claim.

20 In the accompanying drawings, forming part of this specification, Figure 1 is a perspective view of my invention, showing it in operative position on the can; and Fig. 2 is a side elevation of the same.

25 In the practice of my invention I employ a bar B, having an upwardly-extending loop or hood B', adapted to carry a revolvable cutting-disk b, mounted on an axis b', secured in the hood B'. The downwardly-extending end B² of the bar B carries a horizontal handle D, with which to revolve the bar B, and will 30 hereinafter be referred to. The bar B is further provided with a series of perforations B³, adapted for engagement with the prong or 35 spur C' of the removable handle C. This spur acts as a pivot around which the bar B

revolves. It is also used independently as an ice-pick when removed from the bar B.

In operation the bar B is placed diametrically across the top of a can A, and the prong 40 C' of the removable handle C is entered into one of the holes B³ of the bar B at or near the center of the can A and forced downward through the can, thereby acting as a pivot about which the bar B is made to revolve by 45 applying pressure to the handle D, causing the disk b to cut a circular piece from the top of the can. The prong C' of the handle C is long and tapering and adapted to be used, further, as an ice-pick.

Having thus described my invention, what I claim as new, and desire to secure by Letters Patent, is—

A combined can-opener and ice-pick, embodying a bar provided with a series of holes 55 therein, a yoke formed on one end of said bar, a revolving cutter journaled in said yoke, an arm extending downwardly from said yoke and provided with a suitable handle, and an ice-pick adapted to enter one of said holes 60 and pierce the metal of the can and serve as a pivot for the cutter, substantially as shown and described.

In testimony that I claim the foregoing as my invention I have signed my name, in presence of two witnesses, this 7th day of September, 1897.

JOHN BRADY.
